ALFRED M. THOMSON, OF NEWARK, NEW JERSEY, ASSIGNEE TO JOSEPH MERCADANTE,
OF NEW YORK, N. Y.

REFRIGERATING APPARATUS.

Application filed October 25, 1926. Serial No. 143,900.

This invention relates to refrigeration systems, and more particularly concerns a refrigerating or heat absorbing unit for use in connection with systems of this type.

5 In one general type of modern refrigeration system, apparatus is provided for subjecting a suitable refrigerant to a cycle of operations, the refrigerant being successively compressed, liquefied by cooling in a condenser, passed through a suitable expansion valve into a refrigerating or heat absorbing unit where it is gasified, and returned again to be compressed. The heat absorbing or refrigerating unit is preferably installed in the cooling chamber of a suitable refrigerator, or is otherwise disposed in a space where it is desired to absorb heat. In refrigeration systems of this type designed for household use, the refrigerating unit is usually designed to serve the double purpose of cooling the refrigerator and of providing compartments in which liquids, desserts or other foods may be frozen. In order to accomplish these functions, it is desirable among other things, that the refrigerating or heat absorbing unit be constructed to present a maximum surface area for heat absorbing purposes, that the freezing compartments be surrounded by passages containing the refrigerant, and that the entire heat absorbing unit occupy a minimum space.

One form of heat absorbing unit which has been extensively used consists, in general, of a pair of horizontally disposed vertically spaced drums or headers connected by two or more rows of vertical pipes or tubes, which rows are spaced apart to form a freezing compartment therebetween. This type of unit presents a large heat absorbing surface, but has certain disadvantageous features. Because of the large number of pipe connections which must be made, the assembling of a unit of this type is a slow and expensive process, and the finished unit is of a rather weak and non-rigid construction and is therefore likely to develop leaks.

With the above and other considerations in mind, it is proposed in accordance with the present invention to provide a novel form of heat absorbing unit for refrigeration systems, and more particularly it is proposed to provide a heat absorbing unit

of this type which offers a maximum heat absorbing surface area and which is of rigid and simple construction.

It is a further object of the present invention to provide a heat absorbing unit of greatly improved and simplified design, which unit may for this reason be inexpensively and readily manufactured and assembled.

It is a still further object of the present invention to provide a unit of this type which is formed of a minimum number of parts.

Other specific objects, advantages and characteristic features of the present invention will become apparent as the description thereof progresses.

In describing the invention in detail, reference will be made to the accompanying drawings in which—

Figure 1 is a sectional side view of the heat absorbing unit of the present invention, certain parts being broken away to show the interior construction thereof;

Figure 2 is a sectional view taken along the line 2—2 of Figure 1;

Figure 3 is a sectional view taken along the line 3—3 of Figure 2; and

Figure 4 is a fragmentary view of a modified embodiment of the present invention.

The refrigerating unit of the present invention comprises in general a plurality of rows of substantially vertical channels or passages for carrying the refrigerant, which rows of passages are formed to enclose a number of freezing compartments, together with suitable cross channels for admitting the refrigerant to the vertical channels and an upper drum or header to which the upper ends of the vertical channels are suitably connected and through which the refrigerant is conducted away from the unit.

Referring to the drawings, the heat absorbing unit of the present invention includes a cylindrical drum or header 1 which is disposed horizontally and is provided with a suitable removable cover or head 2, secured to one end thereof by the bolts 3, as shown, a gasket 4 being provided to insure a tight closure. A large metallic body 5 is preferably enclosed within the header 1 for the purpose of absorbing heat when the refrigeration system is not in operation, as

more fully described in my co appended application Serial Number 197,788, filed June 10, 1927. The head 2 of the drum 1 is provided with an enlarged portion 6 carrying two outlet pipe connections 7 and 8, a cut-off valve V, and, on the inner face thereof, a swivel mechanism 9 carrying an outlet pipe 10 supported by a float 11. The cut-off valve V may take any suitable form, and as shown, comprises a valve stem 12 surrounded along its outer portion by the packing material 13 and carrying a gate or plug 14 for co-operation with the opening 15 leading to the swivel mechanism 9. The outer end of the valve stem 12 is preferably enclosed by a cap 16 to prevent any unauthorized or accidental manipulation of this valve. As the swivel mechanism 9 and the float supported outlet pipe 10 form no part of the present invention and are fully described in my co appended application, identified above, they will not be described herein, it being sufficient in connection with the present invention to understand that the refrigerant is conducted out of the header 1 through the pipe 10 and the swivel mechanism 9.

The cylindrical wall of the header 1 is provided with three rows of equally spaced openings 17, extending from end to end thereof. Two of these rows of openings 17 are located on the sides of the header 1 along a horizontal plane through the axis thereof, and the third row extends along the lower face of the cylindrical wall as most clearly shown in Figures 1 and 2.

Referring now more particularly to the construction of the circulating passages which comprises an important part of the present invention, these passages are formed by three co-operating plates or sections A, B and C, made of a suitable heat conducting metal such as steel. The section A is somewhat trough shaped, having a substantially U-shaped cross section as shown in Figure 2. The two vertical walls 18 and 19 of the section A are turned toward each other at their upper ends to form the horizontal extensions 20 and 21 respectively. The sections B and C are substantially identical and have the general form of open or incomplete cylinders, their inner walls 22 lying in co-operating relation at the center of the unit, and their lower and outer walls 23 and 24 lying in co-operating relation with the walls 18 and 19 of the section A. The sections A, B and C are provided with a plurality of equally spaced, parallel, semi-circular grooves or depressions 25 which co-operate, when the sections are placed together as shown, to form a plurality of tubular passages as shown in Figures 1 and 2. The outer and lower walls 24 and 23 of the sections B and C co-operate respectively with the outer walls 18 and 19 and the lower wall 26 of the

section A to form the vertical side passages 27 and the horizontal lower passage 28, while the inner walls of the sections B and C co-operate to form the vertical central passage 29. The sections A, B and C are preferably secured together along the plane surface 30 thereof between the grooves 25 by means of spot welding or by any other suitable process. The joints between the sections need not be tight except at the edges thereof, where the co-operating sections may be soldered, crimped over one another or otherwise suitably secured together to form a tight joint.

The sections A, B and C thus secured together present three rows of substantially circular openings at the upper ends of the vertical passages 27 and 29, and the sections are soldered or otherwise suitably secured to the cylindrical wall of the header 1 with these openings in communication with the rows of openings 17 therein. The sections forming the passages 27 and 29 preferably extend beyond the ends of the header 1 as shown in Figure 1, and diagonal passages 31 and 32, formed by co-operating grooves on the sections A, B and C, are provided to connect the vertical passages at the extreme ends of the unit with the header 1.

An internally threaded coupler 33 is suitably secured to an opening 34 in the center of the lower wall 26 of the section A. An angle fitting 35 is preferably provided to connect a suitable inlet pipe 36 to this coupler, and in the embodiment shown, a valve T of suitable construction is provided to control the flow of refrigerant to the heat absorbing unit through the angle fitting 35. As shown, this valve T is of a construction similar to that of the valve V at the outlet of the header 1, having a stem 37, a packing means 38 and a suitable cap 39 enclosing the operating end of the stem.

The vertical walls of the sections B and C are provided with a plurality of equally spaced oppositely disposed extensions or brackets 40. These brackets may be formed in any desired manner, but are preferably pressed out of the sheet material forming the sections B and C on the surfaces of the semi-circular grooves 25 thereon. The brackets 40 are arranged to carry a plurality of horizontal partitions or shelves 41 for the reception of drawers, compartments or other containers in which liquids or desserts may be frozen. The upper-most of the partitions 41 serve to separate the freezing chamber from the header, and these partitions are preferably lagged or covered with a suitable heat insulating material 42. This layer of heat insulating material between the freezing chamber and the header 1 serves to prevent the transmission of heat from the header to the freezing chamber, the header being normally at a slightly higher temper-

ature than the freezing chamber while the system is in operation.

Referring now to the modification shown in Figure 4, the sheet metal sections of the refrigerating unit, portions of two of which are shown in the figure, are formed with substantially semi-circular cross grooves or depressions 43 connecting the grooves 25 therein, the co-operating sections being welded or otherwise secured together at the spaced plane surfaces 44. This construction forms a plurality of cross channels or passages at right angles to each other, the edges 45 of the sections being in continuous communication and being suitably sealed together. By using three co-operating sections of this construction in place of the sections A, B and C described above, a heat absorbing unit is provided in which the refrigerant may circulate in horizontal as well as vertical planes in all of the walls thereof. This construction permits a more thorough circulation of the refrigerant, and thereby equalizes the temperature of the heat absorbing surfaces of the unit to a slightly higher degree than does the construction of Figure 2.

In the operation of the heat absorbing unit of the present invention, the refrigerant, in liquefied form, is admitted through the angle fitting 35 and the valve T to the point where the lower horizontal passages and the central vertical passage 29 communicate. The liquid refrigerant circulates through the passages 27, 28 and 29, absorbing heat from the walls of the sections A, B and C and thus absorbing heat from the cooling chamber in which the unit is installed. As the temperature of the refrigerant rises the refrigerant passes up through the passages 27 and 29 into the header 1. The absorption of heat by the refrigerant causes the boiling thereof, and in this manner the refrigerant becomes gasified and passes off through the outlet pipe 10, the swivel mechanism 9 and the outlet pipe connection 8, the system being preferably designed to maintain the liquid level at some point within the header 1.

The construction of the heat absorbing unit of the present invention presents many obvious structural and operating advantages. The circulating passages of the unit are formed of only three separate sections, and these sections may be quickly secured in co-operating relation by a simple process such as spot welding. The sections may be quickly and cheaply pressed or stamped from sheet metal, and due to their corrugated or grooved formation they provide a very strong and rigid construction, the joints of which are not likely to become loosened by rough handling during installation. The unit of the present invention provides a very large surface area for heat

absorption, the corrugations on the surface of the unit greatly increasing the surface area exposed over that which would be presented by a plane surface. Due to its strong and rigid construction, the heat absorbing unit of the present invention may be formed of comparatively thin sheet metal, and for this reason the completed unit is of very light weight and is therefore easily and cheaply handled, shipped and installed.

Although the heat absorbing unit of the present invention has been described in connection with one specific construction, it should be understood that the invention is not limited in its scope to the exact construction shown, and that many changes, modifications and additions may be made without departing from the scope of the invention as defined by the appended claims.

I claim:

1. In a heat absorbing unit, a plurality of sections of grooved sheet material co-operating to form a plurality of rows of vertical passages connected by rows of horizontal passages, the number of sections employed being equal to the number of vertical rows of passages.

2. In a heat absorbing unit, three co-operating sections of grooved sheet material forming three spaced rows of circulating passages and two communicating rows of passages connecting said spaced rows of passages at one end thereof.

3. In a heat absorbing unit for refrigeration systems, a large section of grooved sheet material of substantially U-shaped cross section and two smaller co-operating sections of grooved sheet material within said large section, said small sections co-operating with each other and with said large section to form three vertical rows of circulating passages connected at their ends by horizontal rows of circulating passages.

4. In a heat absorbing unit, a grooved outer section of sheet metal of substantially U-shaped cross section having vertical side walls and a bottom wall, two inner sections of grooved sheet metal within said outer section and each having vertical side walls and a horizontal bottom wall, the grooves on one of the side walls and the bottom wall of said inner sections co-operating with the grooves on said side and bottom walls of said outer section to form communicating outer vertical and lower horizontal rows of passages, and the grooves on the other side walls of said inner sections co-operating to form a central row of vertical passages communicating with said lower horizontal row of passages.

5. In a heat absorbing unit, a grooved outer section of sheet metal of substantially U-shaped cross section having vertical side walls and a bottom wall, two inner sections of grooved sheet metal within said outer

- section and each having vertical side walls and a horizontal bottom wall, the grooves on one of the side walls and the bottom wall of said inner sections co-operating with the grooves on said side and bottom walls of said outer section to form communicating outer vertical and lower horizontal rows of passages, and the grooves on the other side walls of said inner sections co-operating to form a central row of vertical passages communicating with said lower horizontal row of passages, and means for connecting the upper ends of said outer and central vertical rows of passages.
15. 6. In a heat absorbing unit for refrigeration systems, a plurality of grooved sheet metal sections co-operating to form the walls of a plurality of spaced rows of vertical passages and the walls of a plurality of rows of horizontal passages connecting said vertical passages, supporting means on the portions of said sections forming the vertical walls of said passages, and partitions supported between said supporting means on adjacent walls of said rows of vertical passages.
7. In a heat absorbing unit for refrigeration systems a plurality of rows of vertical passages connected by rows of horizontal passages, said passages being formed of a plurality of co-operating sections of grooved sheet metal integral supports on the adjacent walls of said rows of vertical passages and vertically spaced partitions carried by said supports.
8. In a heat absorbing unit for refrigeration systems, a plurality of sections of grooved sheet metal co-operating to form a plurality of spaced parallel rows of vertical passages connected by rows of horizontal passages, the number of sections employed being equal to the number of vertical rows of passages, a plurality of supporting brackets formed integral with at least some of said sections forming said vertical passages, and shelves supported between said rows of vertical passages on said brackets.
9. In a heat absorbing unit, a plurality of plates of grooved sheet material each co-operating with a single plate of grooved sheet material to form a plurality of spaced parallel rows of passages, integral extensions on said plates and partitions extending between said parallel rows of passages and supported by said extensions.
10. In a heat absorbing unit, a plurality of sections of grooved sheet material co-operating to form a plurality of spaced vertical rows of passages connected in their lower ends by horizontal rows of passages, a header connecting the upper ends of said vertical rows of passages, a plurality of supporting brackets formed integrally with the walls of said vertical rows of passages, partitions supported by said brackets between said vertical rows and dividing the space there-between into compartments, and a heat insulating partition between the uppermost of said compartments and said header for preventing heat interchange between said header and said compartments.
11. In a heat absorbing unit, a plurality of sections of grooved sheet material co-operating to form a plurality of spaced vertical rows of passages connected at their lower ends by horizontal rows of passages, a header connecting the upper ends of said vertical rows of passages, means secured to an opening in the section forming said lower horizontal passages for admitting a refrigerant to said unit, and means in said header for withdrawing said refrigerant from said unit.
12. In a heat absorbing unit for refrigeration systems, a plurality of sections of sheet material having intersecting grooves thereon, said sections co-operating to form walls having a plurality of spaced rows of intersecting passages therein.
13. In a heat absorbing unit, a plurality of sections of sheet material having intersecting grooves thereon, said sections co-operating to form a plurality of spaced vertical walls and connecting horizontal walls, said walls containing rows of parallel intersecting passages.
14. In a heat absorbing unit, a plurality of sections of sheet metal having rows of intersecting grooves thereon, said rows being substantially at right angles to each other, said sections co-operating to form a plurality of spaced vertical walls and connecting horizontal walls, and said grooves on said sections co-operating to form parallel rows of passages in said walls, said rows intersecting at substantially right angles.
15. In a heat absorbing unit, a plurality of sections of sheet metal having rows of intersecting grooves thereon, said sections co-operating to form a plurality of spaced vertical walls connected at their lower ends by horizontal walls, the number of sections used being equal to the number of vertical walls, and the grooves on said sections co-operating to form a plurality of intersecting passages in said walls, and a drum connecting the passages in said vertical walls at their upper ends.
16. In a heat absorbing unit, three co-operating sections of grooved sheet material contacting with each other at certain points, spot welded together at these points, and forming three spaced rows of circulating passages and two communicating rows of passages connecting said spaced rows of passages at one end thereof.
17. In a heat absorbing unit, a plurality of sections of grooved sheet material cooper-

ating to form a plurality of spaced parallel rows of vertical passages connected by a row of horizontal passages, said rows of vertical passages forming the side walls of a plurality of compartments.

18. In a heat absorbing unit, a plurality of sections of corrugated sheet material co-

operating to form a plurality of spaced parallel rows of vertical passages connected at one end by a row of horizontal passages, and a separate header connecting the other ends of said rows of vertical passages.

In testimony whereof I affix my signature.

ALFRED M. THOMSON.
